Primary Examiner—Cathy Anne MacCormac*Attorney, Agent, or Firm*—R. William Graham[57] **CLAIM**

The ornamental design for the combined bird perch and chain, as shown and described.

DESCRIPTION

FIG. 1 is a front elevational view of a combined bird perch and chain showing our new design turned counter clockwise at a 45 degree angle to FIG. 2;

FIG. 2 is a right side elevational view thereof;

FIG. 3 is a bottom view thereof; and,

FIG. 4 is a top view thereof.

The perch member depicted in FIGS. 1 and 2 is noted as having the color teal on shaded portions.
